IRVING ROSENBLoom INVENTOR.

BY Bennett H. Levenson.

ATTORNEY.

UNITED STATES PATENT OFFICE

130,446

DESIGN FOR A CORER OR SIMILAR ARTICLE

Irving Rosenbloom, New York, N. Y.

Application June 18, 1941, Serial No. 101,506

Term of patent 7 years

To all whom it may concern:

Be it known that I, Irving Rosenbloom, a citizen of the United States of America, residing in New York city, county of New York, and State of New York, have invented a new, original, and ornamental Design for a Corer or Similar Article, of which the following is a specification, reference being had to the accompanying drawing, forming part thereof.

Fig. 1 is a front perspective view of a corer or similar article showing my new design.

Fig. 2 is a bottom plan view thereof.

I claim:

The ornamental design for a corer or similar article, substantially as shown.

IRVING ROSENBLOOM.
